United States Patent [19]

Weder

[11] Patent Number: Des. 380,173

[45] Date of Patent: ***Jun. 24, 1997

[54] FLOWER POT COVER

[75] Inventor: Donald E. Weder, Highland, Ill.

[73] Assignee: Southpac Trust International, Inc.,
Oklahoma City, Okla.[*] Notice: The portion of the term of this patent
subsequent to Sep. 26, 2009, has been
disclaimed.

[**] Term: 14 Years

[21] Appl. No.: 42,001

[22] Filed: Jul. 28, 1995

[57] CLAIM

The ornamental design for a flower pot cover, as shown and described.

DESCRIPTION

FIG. 1 is a perspective view of my new flower pot cover design;

FIG. 2 is a top plan view thereof;

FIG. 3 is a bottom plan view thereof;

FIG. 4 is a side elevational view thereof, all sides being identical;

FIG. 5 is a side elevational view of the design of FIG. 1, the only difference being the angle of the skirt; and,

FIG. 6 is a side elevational view of the design of FIG. 1, the only difference being the angle of the skirt.

The flower pot cover has no substantial thickness.

1 Claim, 1 Drawing Sheet
